UNITED STATES PATENT OFFICE

107,790

DESIGN FOR A COMBINATION JEWELRY DISPLAY BOX

Reuben Parness, Brooklyn, and Sam Sweet,
Bronx, N. Y.

Application March 9, 1937, Serial No. 68,088

Term of patent 3½ years

To all whom it may concern:

Be it known that Reuben Parness, residing in Brooklyn, county of Kings, and State of New York, and Sam Sweet, residing in the Bronx, county of the Bronx, and State of New York, and both citizens of the United States, have invented a new, original, and ornamental Design for a Combination Jewelry Display Box, of which the following is a full, clear and exact description.

In the accompanying drawing forming a part of this application—

Fig. 1 is a perspective view of a combination jewelry display box with the design, shown in the closed position.

Fig. 2 is a perspective view showing the box partially open.

Fig. 3 is a perspective view showing the box completely open.

We claim:

The ornamental design for a combination jewelry display box, as shown and described.

REUBEN PARNESS.
SAM SWEET.
